UNITED STATES PATENT OFFICE

GASTON VAN COPPENOLLE, OF ROCHECORBON, FRANCE

SPINNING MACHINE, TWISTING FRAME, REELING ON APPARATUS AND LIKE MACHINE
FOR WINDING THREADS AND THE LIKE

Application filed May 3, 1929, Serial No. 360,210, and in France May 21, 1928.

Applications have been filed in France, on the date of May 21st, 1928, and in Germany, on the 23rd June, 1928, No. C. 41,640.

This invention relates to spinning and twisting machines and more particularly to an improved machine embodying the principles described in my prior application No. 274,579, dated May 2nd, 1928, wherein the yarn is wound on a dragged bobbin by means of a driven tube or flier carrying yarn guides which impart an adjustable tension to the yarn.

One object of the invention is to provide a spinning or twisting machine of the character described wherein the driven tube or flier is of uniform internal diameter and is carried by two annular ball bearings spaced apart from one another so as to lie at different levels and carried in fixed rails.

20 A further object of the invention is to provide a bobbin holder for mounting a dragged bobbin on a dead spindle, which bobbin holder consists of two parts, viz. a lower part nonrotatably supported by the spindle and an upper part coupled to the lower part by a braking device and carried on a centre bearing support on the upper end of the spindle.

Another object of the invention is to provide improved doffing and thread severing arrangements for spinning or twisting machines in which a number of spindles and bobbin holders are mounted on a spindle supporting table which is rotatable so as to bring any one of the spindles and bobbin holders into the operative position and to allow doffing of the filled bobbin.

Other objects of the invention will appear in the following detailed description with reference to the accompanying drawings in which:—

Figure 1 is a front elevation showing the general arrangement of the essential parts of a spinning machine constructed according to the present invention.

Figure 2 is a vertical sectional view through one of the spindles of the machine drawn to an enlarged scale and showing the dead spindle, the two-part bobbin holder and the mechanism for rotating the spindle supporting table for the purpose of bringing any

one of the spindles carried by that table into the operative position.

Figure 3 is a plan view of the parts shown in Figure 2.

Figure 4 is an enlarged detail view showing the arrangement of the yarn guides and knee brake.

Figure 5 is an enlarged detail view of mechanism which permits an extra lowering movement of the spindles additional to the ordinary lifter motion to allow doffing of the filled bobbin and adjustment of the spindle supporting table to move a new spindle into the operative position.

Figure 6 is a detail plan view showing the operating handle for rotating the spindle carrying table.

Figure 7 is an enlarged elevation showing certain of the parts shown in Figure 6 and

Figure 8 is a plan view similar to Figure 7 with the flier tubes and tube rail omitted.

The machine illustrated in the drawings is provided with two driven tubes or fliers 6 (see especially Figures 2 and 3) which have smooth cylindrical inner faces and are carried by external annular bearings 9 (Figure 2), supported by two fixed rails 10 and 11 disposed at different levels. Each of the ball bearings 9 is fitted in a recess in the rail 10 or 11 and is protected by a cover 12 or 13 secured to the rail 10 or 11.

Each of the fliers 6 carries one or more yarn guides 84 by which the yarn is wound on a dragged bobbin carried by a two part bobbin holder mounted on a dead spindle 22. Each yarn guide 84 is mounted on a pivot pin or stud 85 (Figure 4) fixed to the tube or flier 6 and is controlled by a spring 89 which imparts tension to the thread. The bobbin holder consists of two parts viz. a

lower part 21 which is supported on a shoulder near the lower end of the spindle 22 and is held against rotation by a key or pin 23, and an upper part 25 which is supported by a central ball bearing 31 bearing on the upper end of the spindle 22 and is coupled to the part 21 by means of a frictional braking device 26 carried by the part 25 and having frictional engagement with the inner surface of the part 21.

The flier 6 is driven by a wharve or pulley 15 in the usual way and its lowered edge is bevelled to form a knife edge 7, which acts as an automatic thread cutter as hereinafter described.

- The machine is provided with four dead spindles 22 arranged as shown in the plan view (Figure 3) and rigidly secured to a spindle supporting table 39 (Figures 2 and 10 8) which is rotatably mounted about a pin 40 centred in a supporting plate or bracket 53. The table 39 bears on the upper face of a toothed wheel 47 which is supported on the bracket 53 and centred by a boss 39a projecting downwards from the table 39, the table 39 being pressed down on the wheel 47 by a pull spring 50 which acts on the pin 40 and thence through a thrust bearing 41 upon the table 39.
- 15 20 The table 39 is capable of being rotated about the pin 40 and is normally locked in one of four possible positions by means of projections (not shown) on the table 39 engaging fixed recesses.
- 25 30 The rotary movement of the table is effected by a sliding rack 57 meshing with the toothed wheel 47 and controlled by a hand lever 122 (Figures 1, 6 and 7) which is mounted on a pivot 121 fixed to the bracket 53 and has a slot 123a engaging a pin 123 which is fixed to the rack 57 and projects through a slot 123b in the bracket 53. The wheel 47 is capable of rotating the table 39 in the clockwise direction only (Figure 8) 35 by means of a pawl 55 adapted to engage consecutively with four ratchet teeth 44 fixed to the table 39 and symmetrically disposed about its centre. The table 39 is also provided with downwardly projecting pins or 40 bosses 45 which bear on inclined camways 46 formed on the wheel 57 so that a rotation of the wheel 57 through a quarter of a turn in the clockwise direction raises the table 39 sufficiently to disengage its projections from 45 the fixed recesses which hold it in any one of its working positions.

The normal lifting and lowering movements of the spindles 22 necessary for building the bobbins are effected by the usual cam 50 action through a shaft 61 (Figures 1 and 5) which carries a pinion 62 gearing with a rack 63 (see Figure 1). The rack 63 is fixed to a pair of vertical sliding "pokers" 70 which are mounted in fixed guides (not shown) and 55 which carry the supporting plate or bracket 53. The weight of the parts fixed to the sliding pokers is counter balanced in the usual way by a weight 78 attached to a chain 71 which passes over fixed pulleys 75, 76 and is 60 attached to the bracket 53.

The cam mechanism for controlling the lifting and lowering movements necessary for building the bobbins is coupled to the shaft 61 by a chain wheel 96 which is slidably and rotatably mounted on the shaft 61

and is formed with a toothed clutch member 96a adapted to engage a corresponding toothed clutch member 94 fixed on the shaft 61 for the purpose of driving this shaft.

The chain wheel 96 carrying the clutch member 96a is controlled by two springs viz. a spring 100 interposed between the two clutch elements and tending to press them apart and a spring 101 interposed between the chain wheel 96 and a hand wheel 103 75 which engages a screw thread 103a on the shaft 61, and can be rotated relatively to the shaft for the purpose of increasing or diminishing the tension of the spring 101. The shaft also carries an arm 107 on which is mounted a spring loaded pin 106 capable of engaging any one of a number of openings 103 formed in the hand wheel 102. The shaft 61 can be locked against rotation when required by engaging a loose pin 111 through an opening 108a formed in a lug attached to the fixed frame and into one of a number of openings 109 formed in a disc 108 fixed to the shaft 61.

80 85 90 95 From the above description taken in conjunction with the accompanying drawings it will be seen that I have provided a spinning or twisting machine of the character hereinbefore first referred to wherein the driven tube or flier 6 is of uniform internal diameter and is carried by two annular ball bearings spaced apart from one another so as to lie at different levels and carried by the fixed rails 10 and 11.

100 105 110 It will also be seen that I have provided improved doffing and thread severing arrangements in which a number of spindles and bobbin holders are mounted on a spindle supporting table which is rotatable so as to bring any one of the spindles and bobbin 102 holders into the operative position and to allow doffing of the filled bobbin.

110 The operations of doffing and thread severing are effected as follows:—

115 After the machine has been stopped the hand wheel 102 is rotated by hand in the direction to release the tension of the spring 101 and to bring one of the holes 103 into engagement with the pin 106 thereby releasing the drive between the clutch elements 96a and 94 and coupling that hand wheel 102 to the shaft 61 through the arm 107. After this has been done the hand wheel 102 can be used to rotate the shaft 61 for the purpose of lowering the spindle supporting table 39 to 120 the position indicated in dotted lines in Figure 1 so as to free all the spindles 22 from the fliers 6 to permit rotation of the spindle supporting table 39. The loose pin 111 may then be engaged in through the opening 108a into one of the openings 109 in the disc 108 for the purpose of locking the spindle supporting table temporarily in the lowered position.

125 130 135 The hand lever 122 is then moved to the

left (Figure 4) so as to rotate the wheel 47 in the clockwise direction thereby lifting the spindle supporting platform 39 by the action of projections 45 and cams 46 so as to disengage the projections on the table 39 from the recesses. The hand lever 122 is then returned to its original position with the result that the wheel 47 is rotated in the anti-clockwise direction and rotates the table 39 through a quarter of a revolution by engagement of the pawl 56 with one of the teeth 44. After the table 39 has been thus rotated through a quarter of a revolution, the projections on the table 39 fall into fixed recesses so that the table is locked in its new position.

After the table 39 has been rotated through a quarter of a revolution in this way so as to bring two fresh spindles 22 into the operative positions it is lifted to the winding position shown in full lines in Figure 1 by rotation of the hand wheel 102, after which the pin 106 is disengaged from the hole 103 and the hand wheel 102 is turned relative to the shaft 61 so as to press the spring 101 and re-engage the clutch elements 96a and 94.

The machine is then re-started and the ends of the threads wound on the finished bobbins are automatically severed by the knife edge 7.

During the lowering of the spindle supporting table 39 the thread attached to the bobbin which has been wound is drawn down through the tube 6 so that the subsequent rotation and raising of the spindle supporting table causes the thread to bear against the knife edge 7 at the lower end of the tube 6 because the thread is brought into the position indicated by the dotted lines in Figure 1. Consequently when the machine is restarted the rotation of the knife edge 7 cuts the thread automatically.

During the operation of the machine the clutch elements 94 and 96a drive the shaft 61 for effecting the lifting and lowering movement for building the bobbins and in the event of obstruction to this movement these clutch elements become automatically disengaged.

I claim:—

1. A spinning machine of the character described including a rotatable spindle supporting table, a plurality of spindles mounted upon said table, bobbin holders carried on said spindles, at least one driven flier for co-operating with any one of said spindles, means for lowering said spindles from a winding position to a doffing position, means for rotating said spindle supporting table when the spindles are in the doffing position, means for returning said spindles to the winding position after rotation of said spindle supporting table and means for automatically severing the end of the thread on the full bobbin.

2. A spinning machine according to claim 1 including spindle raising and lowering means for building the bobbins, a shaft for operat-

ing said raising and lowering means, a driving element mounted on said shaft, a releasable clutch for coupling said driving element to said shaft, a hand wheel mounted on said shaft and means for disengaging said clutch at will to enable the spindles to be lowered to the doffing position by rotation of said hand wheel.

3. A spinning machine according to claim 1 including a rack and toothed wheel for rotating said spindle supporting table, a hand operated lever for actuating said rack, and pawl and ratchet teeth for transmitting movement in one direction only from said toothed wheel to said spindle supporting table.

GASTON VAN COPPENOLLE.
